UNITED STATES PATENT OFFICE.

OSCAR WOODWARD, OF BABYLON, NEW YORK, ASSIGNOR TO REMINGTON TYPEWRITER COMPANY, OF ILION, NEW YORK, A CORPORATION OF NEW YORK.

TYPEWRITING MACHINE.

1,342,197.

Specification of Letters Patent. Patented June 1, 1920.

Application filed July 29, 1919. Serial No. 314,049.

To all whom it may concern:

Be it known that I, OSCAR WOODWARD, a citizen of the United States, and resident of Babylon, in the county of Suffolk and State 5 of New York, have invented certain new and useful Improvements in Typewriting-Machines, of which the following is a specification.

My invention relates to typewriting machines and more particularly to type actions therefor.

One object of the invention is to eliminate side strain on the parts of each type action, thereby providing lighter and easier operating type actions, and reducing or entirely eliminating the noise which ordinarily results from the use of a machine in which such side strains are embodied.

A further object of my invention is to provide a simple and efficient pivot bearing construction for parts of the type actions.

To the above and other ends which will hereinafter appear my invention consists of the features of construction, arrangements 25 of parts, and combinations of devices set forth in the following description and particularly pointed out in the appended claims.

In the accompanying drawings wherein like reference characters indicate corresponding parts in the various views,

Figure 1 is a fragmentary detail side elevation with parts in section, showing one of the center type actions of the system and some of the associated parts.

Fig. 2 is a detail fragmentary vertical transverse sectional view, showing portions of several type actions and some of the associated parts.

Fig. 3 is an enlarged detail fragmentary side elevation with parts in section, showing a portion of one of the type actions and some of the associated parts.

Fig. 4 is an enlarged detail side elevation with parts in section, showing the rear end 45 of one of the key levers and its fulcrum.

Fig. 5 is a vertical transverse sectional view taken on the line $x-x$ of Fig. 3 and looking in the direction of the arrow at said line.

The invention is shown in the present instance embodied in a front strike typewriting machine, in which upwardly and rearwardly swinging type bars 1 are mounted in slots 2 of a segment 3, to turn on a pivot wire 4 and strike against the front face of a platen 5. The heel of each type bar is slot-

ted at 6, to receive the stem of a headed pin 7 which is carried by and projects laterally from the upper end of an actuating member, or angular sublever, 8. Each sublever is 60 mounted to work in a slot 9 of a slotted cross-bar or support 10, secured at its ends by screws 11 to the base 12 of the frame of the machine. In the bottom of the support is a groove 13 which extends throughout the 65 length of the bar and transversely of the slots 9 therein. This groove is formed with parallel side walls 14 and 15 and an inclined bottom wall 16. A pivot rod or wire 17 is seated in the groove 13 and extends through 70 a bearing opening in, and constitutes a fulcrum for, each of the angular sublevers 8. In order to retain the pivot rod 17 in place I have provided holding means which, in the 75 present instance, comprises a strip or plate 18 that extends throughout the length of the slotted portion of the support 10. This strip is provided along one edge thereof with a flange 19, which bears against and fulcrums on the support 10, to afford a rock- 80 ing adjustment of the plate. Extending upwardly from the front edge of the plate 18, at intervals throughout the length thereof, are engaging fingers 20, the free ends of each of which is adapted to bear against the 85 pivot rod 17, and maintain it seated against the bottom wall 16 of the groove 13. From an inspection of Fig. 2 it will be seen that each of the fingers 20 is located between adjacent slots 9 in the support, and conse- 90 quently between the sublevers that work in said slots. A suitable number of fingers 20 may be provided. As shown herein, two adjacent slots 9 are contained between each adjacent pair of fingers. The strip or plate 18 is apertured intermediate its edges, and at 95 intervals throughout the length of the strip, to receive the stems of headed screws 21; five screws being shown in the present instance. The threaded ends of the screws are received in tapped openings in the bottom 100 of the support 10. When the screws are tightened, the heads thereof, bearing on the plate, tend to turn it on its fulcrum and force the free ends of the fingers up against 105 the pivot rod 17, and firmly hold it seated against the bottom wall 16 of the groove.

In practice it is very difficult to cut the groove 13 with such accuracy, and to provide a pivot rod of such accurate gage, that there 110 will not be, in some instances, a loose fit between the pivot rod and the parallel side

walls 14 and 15 of the groove. It is to provide always a perfectly tight clamping of the pivot wire in the groove, that I form certain of the walls thereof inclined one to another. Thus, as the pivot wire is forced against the inclined bottom wall 16 of the groove, there is a tendency to force it up the incline and against the wall 15. If the rod is smaller than the distance between the walls 10 14 and 15 the rod will be crowded against the walls 15 and 16, thus forming a three-point bearing between the fingers 20, the wall 15, and the wall 16, which firmly hold the rod against play in its seat. By firmly holding 15 the pivot wire in its seat, in the manner indicated, I provide against any rattling of the parts due to a movement of the pivot wire, and prevent any of the key levers and type bars other than those of the type action 20 in use to make the impression, from "winking" or moving, as is ordinarily the case if the pivot wire be not held firmly in its seat.

In order to enable any individual sublever, or any desired number of sublevers, 25 to be removed from the support 10 after the parts are assembled, I provide screws 9^a which are threaded in tapped openings in the base 12 on opposite sides thereof and in line with the pivot wire 17, the unthreaded ends of said screws entering the groove 13. When these screws are removed, and the pivot rod is relieved from the clamping 30 action of the strip 18, the rod may be displaced longitudinally the required distance through one of the openings previously occupied by a screw 9^a.

The forwardly extending arm 8^a of each angular sublever is slotted at 22, to receive the stem of a headed pin 23 which projects laterally from an upright connecting arm 24 of the associate key lever, or key controlled lever, 25. Each key lever is devoid of lateral bends, extending fore and aft of the machine in a single vertical plane between its key 26 and the point where it is fulcrumed on the fulcrum plate 27 secured to the base of the machine. A front guide comb 28 and a rear guide comb 29 guide each key lever in its movement. It will be seen that each key lever is located directly beneath the slot 9 in which its companion sublever 8 is fulcrumed. This is rendered possible by bending the connecting arm 24 of each key lever so that it is off-set laterally with reference to its key lever, and to the plane of movement of the latter. By this arrangement each type action has the fulcrum of its sublever, that portion of the sublever contained within its bearing slot 9, the slotted arm 8^a, the points of contact between the pin 23 and the sublever, and the fulcrum of the key lever, all located in the same vertical plane, which is the plane of movement of the key lever.

65 It will be understood therefore that in

transmitting motion from each printing key to its sublever, force is directed in a single plane, avoiding all side or lateral strain on the parts in question which might tend to cramp them in their bearings and guides. 70 For example, side strain between the key lever and sublever ordinarily would result in a cramping action between the key lever and its guides 28 and 29, and a lateral deflection of the arm 24. Aside from the increased frictional resistance thus offered to the operation of the type action, a rattling noise is produced by the key lever striking side walls of the guides 28 and 29. The lateral deflection referred to of the arm 75 24 is apt to carry the head of the pin 23 against the slotted arm 8^a of the companion sublever, resulting in further side strain and increased friction on the parts, and producing a snapping or clicking noise by the head of the pin 23 striking the sublever. By my present invention I am enabled to overcome these defects, avoiding the clicking and rattling noises ordinarily produced in other type actions and preventing a sluggishness and undue friction on the parts resulting from side strain thereon and the cramping action thereof. By reason of the fact that there is no cramping action of the key levers in their guides of the present 95 construction, I am enabled to make the guide combs 28 and 29 with narrow guide slots as indicated at 29^a, thus effecting a closer fit between each key lever and the side walls of the slots in the guides, which 100 results in less opportunity for the levers to rattle in the guides, thereby reducing or entirely eliminating the noise thus ordinarily produced.

From an inspection of Fig. 2 it will be 105 understood that each of the type actions at and near the center of the system has the engaging portion of its pin 7 cut by the plane of movement of its key lever thus further avoiding lateral strain on the parts.

From the foregoing description it will be understood that by a simple construction I have provided an easy acting type action which avoids the undue friction and noise ordinarily produced in type actions in which there is a side strain effected between the key controlled levers and the sublevers.

What I claim as new and desire to secure by Letters Patent, is:—

1. In a typewriting machine, the combination of a key controlled lever, and a sublever fulcrumed in the plane of movement of the key controlled lever, one of said levers having a connecting arm off-set laterally from the plane thereof and carrying a pin 120 125 which works in a slot in the other lever, the point of engagement between the pin and the walls of the slot being in the plane of movement of the key controlled lever.

2. In a typewriting machine, the combi- 130

- nation of a key controlled lever having a connecting arm off-set from the plane of movement of said lever and carrying a laterally projecting pin, and a sublever fulcrumed in the plane of movement of said key controlled lever and slotted to receive said pin, the slotted portion of the sublever being in the plane of movement of the key controlled lever.
10. 3. In a typewriting machine, the combination of a key controlled lever of the second order, and an angular sublever fulcrumed in the same plane as the key controlled lever, one of said levers having a connecting arm off-set from its plane of movement and carrying a pin, and the other lever having a slot in which said pin works, the slotted portion of the last mentioned lever moving in the plane of movement of the key controlled lever.
15. 4. In a typewriting machine, the combination of a key lever of the second order having a connecting arm off-set from the plane of movement of said lever and carrying a laterally projecting pin, and an angular sublever fulcrumed in the plane of movement of said key lever and slotted in one of its arms to receive said pin, said slotted arm moving in the plane of movement of the key controlled lever.
20. 5. In a typewriting machine, the combination of a key lever of the second order having an upwardly projecting connecting arm off-set from the plane of movement of said lever, an angular sublever fulcrumed above said key lever in the plane of movement of the latter and having one of its arms moving in said plane and provided with a slot therein, and a laterally projecting pin carried by said connecting arm and working in said slot in the sublever.
25. 6. In a typewriting machine, the combination of a key controlled lever having a connecting arm off-set from the plane of movement of said lever and carrying a laterally projecting pin, a sub-lever fulcrumed in said plane and slotted to receive said pin, the slotted portion of the sublever also moving in said plane, a laterally projecting pin carried by said sublever, and a type bar having a slot in which the pin on the sublever works, the engaging portion of the pin on the sublever being cut by the plane of movement of the key controlled lever.
30. 7. In type actions for typewriting or like machines, a slotted support having a groove that extends transversely of said slots, certain of the walls of said groove being inclined one to another, a pivot rod or wire seated and held in said groove against said walls, and members pivoted on said rod or wire and working in said slots.
35. 8. In type actions for typewriting or like machines, a slotted support having a groove that extends transversely of said slots, certain of the walls of said groove being inclined one to another, a holding device comprising a strip having fingers that extend into said groove between slots in the support and bear against the pivot rod or wire and hold it seated against said walls, and members pivoted on said rod or wire and working in said slots.
40. 9. In type actions for typewriting or like machines, a slotted support having a groove that extends transversely of said slots and has parallel side walls and an inclined bottom wall, a pivot rod or wire in said groove, a holding device comprising a strip having fingers that extend into said groove between slots in the support and bear against the pivot rod or wire and hold it seated against said inclined bottom wall of the groove, and members pivoted on said rod or wire and working in said slots.
45. 10. In type actions for typewriting or like machines, a slotted support having a groove that extends transversely of said slots and has parallel side walls and an inclined bottom wall, a pivot rod or wire in said groove, a holding device comprising a strip having fingers that extend into said groove between slots in the support and bear against the pivot rod or wire and hold it seated against said inclined bottom wall of the groove, and members pivoted on said rod or wire and working in said slots.
50. 11. In type actions for typewriting machines, the combination of a slotted support that has a groove extending transversely of the slots in said support, a pivot rod in said groove, a holding strip provided with fingers which enter said groove and bear against the pivot rod, and provided also with a flange on which the strip may receive a rocking adjustment, means for adjusting said strip to and for holding it in place, and members which are pivoted on said rod and work in said slots.
55. 12. In type actions for typewriting machines, the combination of a slotted support that has a groove extending transversely of the slots in said support, a pivot rod in said groove, a holding strip which extends throughout the slotted portion of said support and is provided along one edge thereof with a series of fingers which enter the groove between slots in the support and bear against the pivot rod, said strip having at its opposite edge a bearing flange to enable the strip to receive a rocking adjustment, screws which engage said strip and adjust it to and hold it in place, and members which are pivoted on said rod and work in said slots.

Signed at the borough of Manhattan, city of New York, in the county of New York, and State of New York, this 24th day of July, A. D. 1919.

OSCAR WOODWARD.
